UNITED STATES PATENT OFFICE.

PIERCE F. GIBBONS, OF OAK PARK, ILLINOIS.

GRATE.

SPECIFICATION forming part of Letters Patent No. 443,759, dated December 30, 1890.

Application filed February 3, 1890. Serial No. 339,088. (No model.)

To all whom it may concern:

Be it known that I, PIERCE F. GIBBONS, a citizen of the United States, and a resident of Oak Park, in the county of Cook and State of Illinois, have invented certain new and useful Improvements in Grates, of which the following is a specification.

This invention relates to improvements in grates especially designed for use in connection with steam-boilers, and more particularly to that class known as "tubular grates," in which the grate-bars are formed of tubes or pipes connected with the boiler in such manner that when heated by the fire of the furnace they produce a circulation of the water from the boiler through the grate-bars.

In all prior forms of tubular grates, so far as I am aware, the grate has been located wholly within the walls of the furnace—a most objectionable construction, because no repairs can be made to any one of the tubes in the grate without first putting the fire out, nor can the tubes be cleaned of the sediment which must necessarily accumulate therein as a result of the precipitations produced by the intense heating of the grate-bars without permitting the fire to go out and then disconnecting every tube of the grate—a proceeding obviously slow and expensive, besides materially interfering with the work of the boiler, rendering it absolutely useless for the time being.

The prime object of this invention is to have the grate-bars readily removable or detachable from the grate and from the outside of the furnace, whereby a disabled bar may be readily removed and a new one substituted in its place without disturbing any of the other grate-bars and without the necessity for putting out the fire.

Another object is to utilize the tubular grate as a feed-water heater for heating the water before its delivery to the boiler, and also for separating and accumulating the sediment, lime, and other scale-forming substances from the water during its passage through the grate.

A further object is to enable the cleaning of the grate-bars and the removal of the sediment collected therein without disconnection of any of the bars and during the continuous working of the furnace, and, finally, to provide certain details in the carrying out of my

invention, all as illustrated in the accompanying drawings, in which—

Figure 1 represents a longitudinal section through a boiler-setting, showing a grate applied thereto embodying my invention; Fig. 2, a transverse vertical section on the line 2 2 of Fig. 1; Fig. 3, a plan view of the grate detached from the furnace; Fig. 4, a plan view of the adjustable grate-support; Fig. 5, a horizontal section on the line 5 5 of Fig. 2, showing devices applied to the grate-bars for cleaning the same; Fig. 6, a longitudinal section through one of the grate-bars on the line 6 6 of Fig. 5; Fig. 7, an end view of one of the couplings for the grate-bars, showing one of the bars in position in section; Fig. 8, an enlarged transverse section through one of the grate-bars, taken on the line 8 8 of Fig. 6; 70 and Fig. 9 an end elevation of a pair of grate-bars, showing the mechanism for simultaneously operating the cleaning devices for the bars.

Similar letters of reference indicate the same parts in the several figures of the drawings.

Referring by letter to the accompanying drawings, A indicates the boiler, B the boiler-setting, and C the grate, composed of tubes or pipes D, connected at their ends by means of couplings E, of any desirable form, each tube being connected with the adjacent tubes on each side by these couplings at its ends, so that all the tubes which constitute the 85 grate-bar will be connected into a continuous pipe, the couplings being hollow to form an uninterrupted passage of substantially the same dimensions as and connecting the pair of tubes screwed or otherwise connected therewith. The grate is arranged so as to preferably stand at a slight angle or incline with the front ends of the tubes and their coupling projecting through the front wall of the furnace in convenient position for the application of a pipe-wrench to each of the grate-bars or tubes, while the inner end of the grate is additionally supported upon a frame F, provided with sockets or recesses for reception of the grate-bars and pivoted to the side 90 walls of the furnace, so that it may be swung forward and lie against the front wall of the furnace, as shown by dotted lines in Fig. 1, whenever it is desired to rake the fire, al-

95

100

though this support might be fixed or any other form of support employed instead thereof.

With one of the end tubes of the grate is connected a pipe G, leading to the inspirator for the water-supply, provided with a valve II for cutting off the supply and with a branch pipe I between the valve II and the tube leading to the boiler at a point near the bottom thereof, which pipe is also provided with a valve J for cutting off the connection with the boiler. Connecting with the pipe G, between the valve II and the pipe I, is still another pipe K, leading from the steam-dome of the boiler (not shown) for introducing steam into the pipe G, and from thence through the grate-bars for blowing out the sediment collected therein, as hereinafter more fully described, this pipe being also provided with a valve L for cutting off the steam. With the other end tube or grate-bar is connected a blow-off or discharge pipe M, having a valve N for closing the same and a pipe O connected therewith between the valve N and the grate-bar, leading to the boiler at a point below the water-line, as more clearly illustrated in Fig. 2, and provided with a valve P for cutting off the supply to the boiler. Thus whenever it is desired to fill the boiler with water the valves J, L, and N will be closed and the inspirator-valve II and the valve P opened, so that the supply of water will first flow through the grate-bars and be raised thereby to the proper temperature and then conducted into the boiler through the pipe O. When, however, the boiler has been properly filled, the valve II will be closed and the valve J will be open, after which when the water in the tubes or grate-bars becomes sufficiently heated it will pass up into the boiler through the pipe O, and the cooler water from the boiler will flow down to the grate through the pipe I, thus keeping up a constant and enforced circulation of the water from the boiler through the grate-bars, as illustrated by the arrows of the drawings. During its passage through the grate-bars, where the water is subjected to the most intense heat, there will necessarily be considerable precipitation of sediment, lime, and scale-forming substances, which will gradually collect in the tubes or bars of the grate instead of being precipitated or carried into the boiler, as would be the case if the water were fed directly into the boiler, to prevent which it has heretofore been common to employ feed-water heaters and filters; but with my invention the employment of such heaters is rendered unnecessary, because my tubular grate, with its facilities for gathering and discharging the sediment and precipitations, performs all the functions of a feed-water heater and filter. To prevent these accumulations from adhering to and choking up the tubes of the grate and for the further purpose of loosening or dislodging any scale-forming substances which may adhere to the tubes, I provide each

tube of the grate, the end (though not shown) as well as the inner tubes, with a thin curved or partially-tubular scraper Q, semicircular or a little more than semicircular in cross-section and of substantially the diameter of the interior of the tubes, the edges thereof terminating in sharp knife-like edges to more effectually scrape the sediment and scale-forming substances from the walls of the tubes. These scrapers are substantially the same length as the tubes and are secured to or terminate in a short shank R, working through a suitable stuffing-box S, screwed or otherwise secured to the coupling E, in which the tubes are screwed. The ends of these shanks projecting beyond the stuffing-boxes may be squared and the scrapers rotated in the tube by means of a crank or key independently of each other; but it is preferred that all of the scrapers should be operated in unison and at a single manipulation by the operator, to which end each of the shanks is provided with a worm-wheel T, meshing with a cross worm-shaft U, journaled in suitable brackets secured to and projecting from the front wall of the furnace, to one end of which shaft is secured a crank-handle V for manually operating, although, if desired, power might readily be applied thereto. By giving the crank-handle an occasional turn the scrapers may be caused at intervals to scrape or loosen all the sediment in the tubes, which will tend to gravitate toward the inner and lower end of the tube.

When the tubes require cleaning—that is to say, whenever it is desirable to discharge this loosened sediment from the tubes—the valves J P are first closed and the valves II and N opened, so that the stream of water from the inspirator will flow through the grate and carry the major portion of the sediment off through the blow-off pipe M, after which the valve II will be closed and the valve L in the steam-pipe leading from the steam-dome will be opened and a blast of steam pass through the grate-bars, which will effectually drive out all of the sediment collected therein, and, if desirable, a small quantity of water may be mixed with the steam. Upon closing the valves H, L, and N and opening the valves J and P the circulation of the water from the boiler through the grate-bars will be re-established, all of which may be done—that is, the cutting off, cleaning the grate, and restoring the circulation—without the slightest interference with the fire in the furnace or with the work of the boiler.

It will be observed that the scrapers are of such length as to not materially interfere with the passage of the water through the couplings, while the tubes are of sufficient diameter to have the proper capacity when occupied by the scrapers, which latter when at rest will obviously stand in almost any position desired, although it is preferable that they should occupy the upper portion of the tube most of the time, in order that the precipita-

tions and sediment may not lodge thereon, and which can readily be accomplished by a proper relation between the crank-handle, worm-shaft, and wheel.

5 Another advantage of this grate is that any one or more of the grate-bars may be removed and from the outside of the furnace independent of all the other grate-bars and without the necessity for putting out the fire in the furnace, for by proper manipulation of the valves the water may be blown entirely out of the tubes of the grate, when one of them may be removed and a new one substituted in its place without a material interruption to the work of the boiler or reduction of the steam therein.

Having described my invention, what I claim, and desire to secure by Letters Patent, is—

20 1. In a grate, the combination, with the tubular grate-bars, of an internal longitudinal scraper locked in each of said bars, said scraper being curved in cross-section to conform to the curvature of the tube and terminating along its sides in knife-like edges, substantially as described.

2. In a grate, the combination, with tubular grate-bars projecting beyond the front wall of the furnace and hollow couplings connecting each bar at its ends, respectively, with the adjacent grate-bars, of a rotary longitudinal scraper located in each of said bars and a shank therefor projecting and working through the couplings at the front end of 35 said bars, furnishing a means for rotating said scrapers, substantially as described.

3. In a grate, the combination, with tubular grate-bars projecting beyond the front wall of the furnace and hollow couplings connecting each bar at its ends, respectively, with the adjacent grate-bars, of a rotary longitudinal scraper located in each of said bars, a shank therefor projecting and working through the couplings at the front end of 45 said bars, a worm-wheel secured to each of said shanks, and a cross worm-shaft meshing with all of said wheels for imparting a simultaneous rotation thereto, substantially as described.

4. In a grate, the combination, with tubular grate-bars projecting beyond the front wall of the furnace, of hollow couplings connecting each inner bar at its ends, respectively, with the adjacent grate-bars, a valved supply-pipe connected with one end grate-bar, a valved pipe connecting said first pipe with the boiler, a valved pipe connected with the other end grate-bar, and a valved pipe also connecting said pipe with the boiler, substantially as and for the purpose described. 50 55 60

5. In a grate, the combination, with tubular grate-bars projecting beyond the front wall of the furnace and hollow couplings connecting each inner bar at its ends, respectively, with the adjacent grate-bars, of a 65 valved supply-pipe connected with one end grate-bar, a valved pipe connecting said first pipe with the boiler, and a valved pipe also connecting said first pipe, between its valve and the grate-bar, with the steam-dome, a 70 valved pipe connected with the other end grate-bar, and a valved pipe also connecting said pipe with the boiler, substantially as described.

6. In a grate, the combination, with tubular grate-bars projecting beyond the front wall of the furnace, hollow couplings connecting each inner bar at its ends, respectively, with the adjacent grate-bars, a rotary longitudinal scraper located in each of said bars, 75 and a shank therefor projecting and working through the couplings at the front end of said bars, furnishing a means for rotating said scrapers, of a valved supply-pipe connected with one end grate-bar, a valved pipe connecting 80 said first pipe with the boiler, and a valved pipe also connecting said first pipe, between its valve and the grate-bar, with the steam-dome, a valved pipe connected with the other end grate-bar, and a valved pipe 85 also connecting said pipe with the boiler, substantially as described. 90
